(57) **CLAIM**

I claim the ornamental design for a single serving hinged container, as shown and described.

DESCRIPTION

FIG. 1 is a perspective view of a single serving hinged container, showing my new design in open condition;

FIG. 2 is a perspective view thereof, in closed position;

FIG. 3 is a side elevation view thereof, in open position;

FIG. 4 is a top plan view thereof; and,

FIG. 5 is a bottom plan view thereof.
